UNITED STATES PATENT OFFICE.

CARL SCHALLER, OF BRUNSWICK, GERMANY, ASSIGNOR TO GRIMME, NATALIS & CO., COMMANDITGESELLSCHAFT AUF ACTIEN, OF BRUNSWICK, GERMANY, A CORPORATION OF GERMANY.

CALCULATING-MACHINE.

1,400,003.

Specification of Letters Patent. Patented Dec. 13, 1921.

Application filed June 19, 1916. Serial No. 104,537.

(GRANTED UNDER THE PROVISIONS OF THE ACT OF MARCH 3, 1921, 41 STAT. L. 1313.)

To all whom it may concern:

Be it known that I, CARL SCHALLER, citizen of the Duchy of Brunswick, Empire of Germany, residing at Brunswick, Germany, have invented certain new and useful Improvements in Calculating-Machines, of which the following is a specification.

My present invention relates to calculating machines of the type in which the numbers and items to be introduced into the calculation are set up through the agency of keys, and in which the result of the calculation is registered in a set of computing wheels mounted on a sliding carriage. Otherwise, the interior construction of the machine is quite immaterial for the purpose of my present invention and may vary widely.

It is the object of my invention to provide means for shifting the traveling carriage stepwise in either direction each step corresponding to one denominational unit; and to locate suitable actuators for such shifting means at the front of the machine.

In the accompanying drawings, I have illustrated an embodiment of my invention, by way of example, it being understood that modifications may be made in the construction and disposition of parts shown without thereby involving a departure from the spirit and scope of my invention.

In the drawings, Figure 1 shows a machine with this invention, partly in side elevation, partly in section. Fig. 2 represents the machine viewed from the rear and partly cut away to show the mechanism by means of which this invention is carried into effect. Fig. 3 is a view similar to Fig. 1 showing the mechanism in another stage of operation. Fig. 4 is a view similar to Fig. 40 but showing the mechanism in the stage of operation represented in Fig. 3.

Referring to the drawings, the sliding carriage *a* which carries the computing wheels (not shown) is provided with a spring actuated latch *b* which cooperates with a rack *c* provided on a part of the machine frame for the purpose of locking the carriage *a* in various positions. On moving the latch *b* out of engagement with the said rack *c*, the carriage *a* is released to be shifted by hand.

The novel means for obtaining an automatic and stepwise shifting of the sliding carriage *a*, each step corresponding in its

extent to one denominational unit, will now be described.

Two actuating levers or keys *d*, *e* crossing the machine from the front to the rear, are provided with key heads at the front side of the machine. The levers are pivotally supported in the rear part of the machine and have extensions which terminate in cam faces *f*, by means of which a lever *h* is swung about its pivot *g* whereby the upper end of the lever *h* acts against a comb edged plate *k* oscillatingly supported on the shaft *i*.

When the plate *k* is caused to swing forward it engages the latch *b* wherever the same may be positioned within its sliding path, and disengages the latch from the stationary rack *c*; see Fig. 3.

The comb edged plate *k* with its shaft *i*, is mounted in a sliding frame *u*, which is guided, by means of pins *v*, in slotted parts *w* secured to the frame of the machine, and although the latch *b* is now in engagement with the teeth of the plate *k*, the carriage *a* may yet be moved in conjunction with the plate *k*. The joint movement is caused in a manner which will now be described.

In accordance with which of the two keys or actuators *d* and *e* is being depressed, the corresponding one of the two stays *l* and *m* will be raised. Both these stays are swingingly suspended on a common yoke *o* which is mounted on the pivot *n*. When owing to the key *e* being depressed, the stay *m* is raised, as illustrated in Fig. 4, the yoke *o* is caused to swing to the left. However, this swinging action of the yoke would be prevented by the second stay *l* which is not set in motion by the key *d*, but for the provision of special means which cause it to move away from the key *d* and thus gain free space to descend while the associated stay *m* ascends, the said means comprising stationary pins *q* that engage slots *p* in the respective stays *l* and *m*. While the yoke *o* swings, the stationary pins *q* form pivots about which the stays are compelled to rock whereby the stay that is not raised by the respective key, is caused to move away from its associated key.

The yoke *o* is formed with an opening *r* through which projects a pin *s* on the sliding frame *u*, and by reason of this construction the yoke is enabled to act upon the

said frame u and to move the same in either direction in conjunction with the comb edged plate k and the carriage a . The extent of the shift thus produced corresponds 5 to the regular distance between two denominational units. The resulting unit shift will be to the left when the key e is set in motion, as illustrated in Figs. 3 and 4. The opposite shift will be produced by a depression of the key d . On releasing the depressed key, the spring k^1 causes the plate k to swing back allowing the latch b to again engage the stationary rack c and become locked thereby. The comb edged 10 plate k together with its sliding frame u is then free to be automatically returned into the initial position by the action of the spring t ; see Figs. 4 and 3.

To insure the proper return into the 20 fixed initial position, no matter whether the shift has been to the left or to the right, a finger x is provided which is loosely suspended from a part of the machine frame and which co-operates with two stationary 25 stops y , y , limiting the swing of the finger x in either direction. The comb plate k is provided with a projection z that engages the finger x from the left when the said plate returns under the action of its spring 30 k^1 after having performed the above described shift to the left, which direction is indicated by the full lined arrow in Fig. 2. When the sliding frame u has been shifted to the right and the comb edged plate k 35 swings back under the action of the spring k^1 into its rearward position, the projection z will then engage the said finger x from the right and move the same against the left stop y .

40 What I claim as my invention and desire to secure by Letters Patent of the United States, is:

1. In a calculating machine, in combination with a sliding carriage, means for automatically shifting said carriage stepwise in either direction, said means comprising an actuator for causing the shift in one direction, a second actuator for causing the shift in a direction opposite to the direction 45 caused by said first actuator, and oscillating means for moving the carriage and loosely engaged and alternately operated by the said actuators for moving the carriage in different directions.

55 2. In a calculating machine, in combination with a sliding carriage, a pair of actuators, a yoke having an oscillating movement and supported on a stationary pivot and having arms loosely and independently 60 engaged by the individual actuators and operative to be swung in one direction by one of said actuators and in the opposite direction by the second of said actuators, and operative connections between said yoke 65 and said carriage whereby said carriage is

shifted in either direction on actuation of said actuators.

3. In a calculating machine, in combination with a sliding carriage, a spring actuated latch on said carriage, stationary means adapted to co-act with said latch in any effective position of said carriage, means for automatically shifting said sliding carriage stepwise in either direction, said means comprising an oscillating device supported on a 70 stationary pivot, an actuator for causing the shift of said device in one direction and a second actuator for causing the shift of the device in a direction opposite to the direction caused by said first actuator, means for moving said latch into inoperative position, and operative connection between said oscillating device and said actuators, whereby on actuation of any of said actuators said latch is caused to assume an inoperative position. 80

4. In a calculating machine, in combination with a sliding carriage, a spring actuated latch on said carriage having a projection, stationary rack means to co-act with said latch and with which said projection engages in any effective position of said carriage, a pair of actuators, a yoke having arms and supported on a stationary pivot and adapted to be swung in one direction by 90 one of said actuators, said actuators having a loose engagement with the arms of the yoke, and in the opposite direction by the second of said actuators, operative connections between said structure and said carriage, whereby said carriage is shifted in either direction on actuation of said actuators, means for moving said latch into inoperative position, and operative connections between the last named means and said actuators, whereby said latch is moved out of its operative position on actuation of any of 95 said actuators, whereafter said carriage is free to be moved in either direction. 100

5. In a calculating machine, in combination with a sliding carriage, a pair of actuating levers, a two-armed yoke oscillatingly supported intermediate its arms, a pair of slotted bars pivotally connected to the ends of said arms having their slots engaging stationary pins and adapted to be raised by said actuators, whereby said structure is caused to swing in one direction on actuation of one actuator and in the opposite direction on actuation of the other actuator, a 110 sliding frame having its sliding path parallel to the sliding path of said carriage, means for movably connecting said frame and said carriage, operative connections between said sliding frame and said structure, whereby said frame is shifted in either direction in accordance with the swinging direction of said structure, and loose operative connections between said actuators and said 115 coupling means, whereby said sliding frame 120 is shifted in either direction on actuation of said actuators. 125

is coupled to said carriage on actuation of either of said actuators.

6. In a calculating machine, in combination with a sliding carriage, a spring actuated latch on said carriage, stationary means adapted to co-act with said latch in any effective position of said carriage, a sliding frame sliding parallel to said carriage, a member mounted oscillatorily on said frame and adapted to co-act with said latch in any effective position of said carriage and simultaneously disengage said latch from said stationary means, said member being normally held away from said latch, a pair of actuating levers, a two-armed structure oscillatorily supported intermediate its arms, a pair of slotted bars pivotally connected to the ends of said arms having their slots engaging stationary pins and adapted to be raised by said actuators, whereby said structure is caused to swing in one direction on actuation of one actuator and in the opposite direction on actuation of the other actuator, an operative connection between said structure and said sliding frame for imparting to the latter a shift in a direction corresponding to the direction of the swinging movement of said structure, means tending to return said frame into central position, and operative connections between said oscillatory member and said actuators, whereby said actuators are enabled to act upon said member to cause the same to engage said latch and simultaneously release the same from said stationary means, whereafter said carriage can be shifted in conjunction with said frame.

7. In a calculating machine, in combination with a sliding carriage, a spring actuated latch on said carriage, stationary means adapted to co-act with said latch in any effective position of said carriage, a pair of actuators, a two-armed structure oscillatorily supported intermediate its arms, each arm having a bar pivotally connected thereto and mounted to slide and swing and loosely detachably engaging one of said actuators, whereby said structure will be swung in one direction by actuation of one of said actuators and in the opposite direction by actuation of the second actuator, means for automatically detaching one of said bars from its respective actuator when the other bar is being operated by its respective actuator, operative connections between said structure and said carriage, whereby said carriage will be shifted in either direction on actuation of said actuators, means for moving said latch into in-

operative position, and operative connections between the last named means and said actuators, whereby said latch is moved out of its operative position on actuation of either of said actuators.

8. In a calculating machine, in combination with a sliding carriage, a pair of actuating levers, a two-armed structure oscillatorily supported intermediate its arms, a pair of bars pivotally connected to the ends of said arms and formed with slots to permit them to slide and swing laterally and adapted to loosely and detachably engage said actuators, whereby said structure is caused to swing in one direction by actuation of one actuator and in the opposite direction by actuation of the other actuator, means for automatically disengaging one of said bars from its respective actuator while the other bar is being operated by its respective actuator, a sliding frame sliding parallel to said carriage, a spring actuated latch on said carriage, stationary means for co-acting with said latch in any effective position of said carriage, a member oscillatorily mounted on said sliding frame and adapted to co-act with said latch in any effective position of said carriage and simultaneously disengage said latch from said stationary means, said member being normally held away from said latch, an operative connection between said sliding frame and said two-armed structure, whereby said frame is shifted in either direction in accordance with the direction of the swinging movement of said structure, means tending to return said frame into central position after each shifting movement, means adapted to coöperate with said frame and comprising two stationary stops for insuring the central position, and operative connections between said oscillatory member and said actuators, whereby said actuators are enabled to act upon said member to cause the same to engage said latch and simultaneously release the said latch from said stationary means, whereafter said carriage can be shifted in conjunction with said sliding frame and through the agency of said structure simultaneously actuated by said actuators.

In testimony whereof I have hereunto set my hand in presence of two subscribing witnesses.
